CAN OPENERS

John Nagy and Wilbert James, New York, N. Y.

Application November 26, 1954, Serial No. 471,473

17 Claims. (Cl. 30—6.1)

This invention relates to can openers of the type adapted to be hooked on the bead of a can and rocked on the bead into a position in which the opener pierces the can top to form a dispensing opening therein. Openers of this type are commonly used for opening beer cans, juice cans, and the like, and conventionally, are equipped with a piercing prong to form the dispensing opening.

It is desirable also to form an air vent opening in the can top, in spaced relation to the dispensing opening, to permit the contents to flow out freely. Accordingly, it has been heretofore proposed to equip an opener with a vent-forming extension prong, adapted to form a vent opening at the same time the dispensing opening is formed.

One object of the present invention is to provide a generally improved tool of the type wherein a dispensing and vent opening are formed substantially simultaneously responsive to a single rocking of the tool about its axis on the periphery of the can top.

Another object of the invention, of considerable importance, is to provide a tool of the type stated which will be novelly designed in such a manner as to result in increased leverage during the operation of forming dispensing and vent openings in the container.

Yet another object is to provide a tool as described which can be fashioned from relatively thin sheet metal material, thus holding the cost down to the maximum extent. This is particularly important in view of the fact that opening tools as described are generally distributed complementarily to purchasers of the beer or other beverage sold in the can.

A still further object of the present invention proposes constructing the opener with an upwardly inclined lever end portion at the tool end of the opener for pressing or driving the vent-forming extension prong through the top of a can.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an opening tool formed in accordance with the present invention.

Fig. 2 is a longitudinal sectional view on line 2—2 of Fig. 1, a can being indicated in dotted lines, the tool being shown in full and dotted lines in its initial and final positions, respectively.

Fig. 3 is a top plan view of the tool.

Fig. 4 is a top plan view of a modified form.

Fig. 5 is a longitudinal sectional view on line 5—5 of Fig. 4.

Fig. 6 is a fragmentary, longitudinal sectional view of a second modification.

Fig. 7 is a fragmentary top plan view of the form of the invention shown in Fig. 6.

The reference numeral 10 has been applied generally to

2

the opener constituting the present invention. The opener is formed from a single piece of sheet metal material, having an elongated, flat body portion 14 which at its tail end is formed with an upwardly offset, longitudinally curved abutment 16. Medially between the opposite sides of the abutment, at the base thereof, a U-shaped slit is formed in the body portion, and the material circumscribed by said slit is struck downwardly and is formed at its free end with an upwardly directed lip, to define a tongue 18 cooperating with the abutment 16 in removing bottle caps of the crown type.

At its head end, the body portion 14 is integral with a short connecting portion 20 which is inclined 45° to the plane of the portion 14. At its lower end, the connecting portion 20 is formed with a widened head portion 22, said head portion being widest at its base end, and being formed with side edges converging toward the head end of the tool, which is upwardly directed and enlarged. Due to the provision of the flat, inclined connecting portion 20, the body portion 14 is disposed in a plane parallel to the plane of the head portion 22, but is offset upwardly from the plane of the head portion 22, to afford increased leverage when the opener is rocked from its dotted to its full line positions of Fig. 2.

In the portion 22 there is formed a V-shaped slit 24 the sides of which are generally parallel to the convergent side edges of the head portion, as best shown in Fig. 2. The slit 24 defines a main or dispensing opening forming prong 26, which is struck downwardly as shown in Fig. 1 out of the plane of the head portion, the prong 26 being disposed in angular relation to said plane as shown in Fig. 2, whereby to form a triangular dispensing opening in the can top when the tool is rocked about the bead of said top to the position thereof shown in full lines in Fig. 2.

Adjacent the base portion of the prong 26, medially between the opposite sides thereof, a U-shaped slit is formed, and the material surrounded by said slit is struck downwardly to provide a hook element 30 having a bent tip that engages under the can top bead.

When the prong 26 is struck out of the material of said portion 22, it leaves convergent side portions on said head portion 22 as shown in Fig. 1, which side portions at their convergent ends merge into an upwardly inclined, enlarged head end lever 31 disposed at a wide obtuse angle to the head portion 22. Between the prong 26 and the head end lever 31, a portion of the material is cut and bent downwardly to form a vent forming prong 32. This is smaller than the main prong 26, and is bent out of the plane of the head and body portions at an angle acutely related to the main prong 26, as best shown in Fig. 2. This arrangement is for the purpose of facilitating the formation of a venting prong of substantial size.

An important advantage of the tool resides in the fact that despite its being provided with longitudinally spaced prongs, both of which must enter the can top when dispensing and vent openings are to be formed, the tool can still be manufactured at relatively low cost, from comparatively thin sheet material.

The upwardly inclined enlarged head end lever 31 provides means by which the vent forming prong 32 can be pressed or driven through the top of a can. The lever 31 can either be pressed by the thumb of a hand grasping the body portion (see Fig. 2) or can be driven by hitting it with the butt of one's hand.

In the form of the invention shown in Figs. 4 and 5, the piercing tool 10a includes a body portion 14a and a head portion 22a. The head portion has ribs 36a and as will be noted from Figs. 4 and 5, the body portion 14a is offset upwardly by a connecting part 20a out of the plane of the head portion, with the inner end portions

37^a of ribs 36^a extending beyond the base of the head portion fully past the offset, thus to strengthen the integral connection of the relatively offset head and main portions. The main prong 26^a has reinforcing ribs 28^a, and a bead-engaging tongue 30^a is struck out of the material of the main prong. The abutment 16^a has a marginal rib 35^a.

The head portion also contains an upwardly inclined enlarged head end lever 31^a to press or drive the venting prong 32^a through a can top. The venting tongue 32^a is provided with a reinforcing rib 34^a formed as a continuation of the convergent ends of ribs 36^a, and the head end lever 31^a is also formed with a marginally extending reinforcing rib merging at its ends into the ribs 36^a.

As shown in Fig. 5, the vent forming prong is formed differently than in the form of the invention shown in Figs. 1-3. The vent forming prong, at its base end, has an approximately semicircular portion, merging at its outer end into a short, straight portion having a filed or beveled point. The general plane of the vent forming prong lies at an acute angle to the head portion 22^a, and is further disposed at an acute angle to the general plane of the dispensing opening forming prong 26^a. The arrangement particularly facilitates the entrance of the vent forming prong into the can top, and due to the semicircular portion that follows the tip part of the vent forming prong into the can top, the initially small vent opening is enlarged by the time the tool reaches its final position.

In this form of the invention, and also in the first form, the main prong is disposed substantially at right angles to the plane of the body portion. This is permitted because the offsetting of the body portion will define a space between said body portion and the side wall of the container, when the tool is being engaged in the can bead preliminary to rocking of the tool about said bead. The fingers of one hand can be inserted in the space to permit grasping of the handle. Then, the tool is rocked upwardly to the position shown in Fig. 2 to form the vent and dispensing openings.

In the form of the invention shown in Fig. 6, the tool 10^b has a body portion 14^b joined by an inclined connecting portion 20^b to a head portion 22^b. A bead-engaging tongue 39^b and a dispensing opening forming prong 26^b are struck out of the material of the head portion.

To this extent, the form of the invention of Figs. 6 and 7 is the same as in the previous forms.

However, instead of the head portion 31^b being disposed over its entire area in the plane lying at an obtuse angle to the plane of the head portion, said lever 31^b has a flat outer end portion offset upwardly from and lying in a plane parallel to the plane of the head portion 22^b, through the medium of an inclined connecting portion 37^b out of the material of which the vent forming prong 32^b is formed. The prong 32^b is straight from end to end in this form of the invention, being disposed in the same angular relation to the head portion and dispensing-opening-forming prong as the venting prong 32 of the first form of the invention.

In all forms of the invention, there is the common characteristic wherein a blank of inexpensive sheet metal material is so formed as to provide, in a single tool, means to simultaneously form, at properly spaced locations, dispensing and vent openings in the can, responsive to a simple rocking movement of the tool from the dotted to the full line position of Fig. 2. Further, all forms of the invention have the common characteristic wherein, beyond the vent forming prong, there is a head end lever which is so located as to be engaged by the thumb of a user's hand, when said hand is grasping the body portion of the tool in a natural manner during the rocking of the tool. This permits, when the vent forming prong initially moves into contact with the surface of the can top, added

leverage to be exerted at the location of the venting prong, in a downward direction, tending to drive the venting prong through the material of the can top.

It is of further importance that the connecting portion 20, 20^a, 20^b is in every instance disposed at an angle of 45° relative to each of the relatively offset, parallel planes of the body and head portions. Due to this arrangement, as the tool is rocked from its dotted to its full line positions of Fig. 2, the connecting portion is disposed counter to lines of force tending to bend the same. This is particularly true as the prongs begin to enter the can top. At this time, at the location of the lower end of the connecting portion, a considerable strain is set up, which would ordinarily tend to bend the tool at this point. However, the connecting portion, being disposed at an obtuse angle to each of the head and body portions, effectively resists this bending moment. At the same time, the connecting portion offsets the body portion outwardly from the can, in the initial position of the tool, to facilitate the insertion of one's fingers through the space between the body portion of the tool and the side wall of the can.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. A piercing tool for forming dispensing and air vent openings in a can top, comprising: a body formed from a single sheet of metal material and including a body portion serving as a handle, a head portion at one end of the body portion having an air vent prong, a main prong struck out of the material of the head portion, said head portion having an outwardly inclined head end lever with an enlarged free end.

2. A piercing tool for forming dispensing and air vent openings in a can top, comprising: a body formed from a single sheet of metal material and including a body portion serving as a handle, a head portion at one end of the body portion having an air vent prong struck therefrom, a main prong struck out of the material of the head portion and spaced from the air vent prong, and reinforcing ribs on said head portion, air vent prong, and main prong, said air vent prong and main prong being tapered, said head portion having an outwardly inclined head end lever with an enlarged free end, the ribs of the head portion being extended longitudinally and centrally of the side portions and terminating behind the air vent prong.

3. A piercing tool for forming dispensing and air vent openings in a can top, comprising: a body formed from a single sheet of metal material and including a body portion serving as a handle, a head portion at one end of the body portion having an air vent prong adjacent the end thereof and struck from the material of the head portion, a main prong struck out of the material of the head portion and spaced from the air vent prong, and reinforcing ribs on said head portion, air vent prong, and main prong, said air vent prong and main prong being tapered, said head portion having an outwardly inclined head end lever with an enlarged free end, the ribs of the head portion being extended longitudinally and centrally of the side portions and terminating behind the air vent prong tip, said ribs having convergent ends traversing the air vent prong.

4. A piercing tool for forming dispensing and air vent openings in a can top, comprising: a body formed from a single sheet of metal material and including a body portion serving as a handle, a head portion at one end of the body portion having an air vent prong adjacent the end thereof and struck out of the material of the head portion, a main prong struck out of the material of the head portion and

spaced from the air vent prong, and reinforcing ribs on said head portion, air vent prong, and main prong, said air vent prong and main prong being tapered, said head portion having an outwardly inclined head end lever with an enlarged free end, the ribs of the head portion being extended longitudinally and centrally of the two prongs and having convergent ends merging into the ribs of the air vent prong.

5. A piercing tool for forming dispensing and air vent openings in a can top, comprising: a body formed from a single sheet of metal material and including a body portion serving as a handle, a head portion at one end of the body portion having an air vent prong struck therefrom and disposed adjacent the end thereof, a main prong struck out of the material of the head portion and spaced from the air vent prong, and reinforcing ribs on said head portion, air vent prong, and main prong, said air vent prong and main prong being tapered, said head portion having an outwardly inclined head end lever with an enlarged free end, the ribs of the head portion being extended longitudinally and centrally of the side portions and merging into the ribs of the air vent prong, said ribs on the main prong and the air vent prong being in pairs and extended in convergent relation, the ribs of the main prong extending at their divergent ends beyond the base of the main prong.

6. A piercing tool for forming dispensing and air vent openings in a can top, comprising: a body formed from a single sheet of metal material and including a body portion serving as a handle, a head portion at one end of the body portion having an air vent prong struck from the material of the head portion, a main prong struck out of the material of the head portion and spaced from the air vent prong, and reinforcing ribs on said head portion, air vent prong, and main prong, said air vent prong and main prong being tapered, said head portion having an outwardly inclined head end lever with an enlarged free end, the ribs of the head portion being extended longitudinally and centrally of the side portions and merging into the ribs of the air vent prong, said ribs on the main prong and the air vent prong being in pairs and extending in convergent relation, the ribs of the main prong extending at their divergent ends beyond the base of the main prong, the ribs of the head portion extending at one end beyond the base of said head portion.

7. A piercing tool for forming dispensing and air vent openings in a can top, comprising: a body formed from a single sheet of metal material and including a body portion serving as a handle, a head portion at one end of the body portion having an air vent prong struck therefrom adjacent the end thereof, a main prong struck out of the material of the head portion and spaced from the air vent prong, and reinforcing ribs on said head portion, air vent prong, and main prong, said air vent prong and main prong being tapered, said head portion having an outwardly inclined head end lever with an enlarged free end, the ribs of the head portion being extended longitudinally and centrally of the side portions and merging into the ribs of the air vent prong, said ribs on the main prong and the air vent prong being in pairs each extended in convergent relation, the ribs of the main prong extending at their divergent ends beyond the base of the main prong, the ribs of the head portion extending at one end beyond the base of said head portion, the body portion being offset upwardly relative to the head portion.

8. A piercing tool for forming dispensing and air vent openings in a can top, comprising: a body formed from a single sheet of metal material and including a body portion serving as a handle, a head portion at one end of the body portion having an air vent prong struck therefrom adjacent one end thereof, a main prong struck out of the material of the head portion and spaced from the air vent prong, and reinforcing ribs on said head portion, air vent prong, and main prong, said air vent prong and main prong being tapered, said head portion having an outwardly inclined head end lever with an enlarged free end, the

ribs of the head portion being extended longitudinally and centrally of the side portions and merging into the rib of the air vent prong, said ribs on the main prong and air vent prong being in pairs each extended in convergent relation, the ribs of the main prong extending at their divergent ends beyond the base of the main prong, the ribs of the head portion extending at one end beyond the base of said head portion, the body portion being offset upwardly relative to the head portion, the ribs of the head portion terminating at said end thereof beyond the offset between the head and body portions.

9. A piercing tool for forming dispensing and air vent openings in a can top, comprising: a body formed from a single sheet of metal material and including a body portion serving as a handle, a head portion at one end of the body portion having an air vent prong struck therefrom adjacent one end thereof, a main prong struck out of the material of the head portion and spaced from the air vent prong, and reinforcing ribs on said head portion, air vent prong, and main prong, said air vent prong and main prong being tapered, said head portion having an outwardly inclined head end lever with an enlarged free end, the ribs of the head portion being extended longitudinally and centrally of the side portions, and merging into the rib of the air vent prong, said ribs on the main prong and air vent prong being in pairs each extended in convergent relation, the ribs of the main prong extending at their divergent ends beyond the base of the main prong, the ribs of the head portion extending at one end beyond the base of said head portion, the body portion being offset upwardly relative to the head portion, the ribs of the head portion terminating at said end thereof beyond the offset between the head and body portions, said main prong being extended substantially at right angles to the body portion.

10. A piercing tool for forming dispensing and air vent openings in a can top, comprising a flat body portion, a flat head portion lying in a plane parallel to and below the plane of the body portion, a connecting portion joining the head and body portions and extending in a plane oblique to the first-named planes, a dispensing-opening-forming prong and a can-bead-engaging prong struck out of the material of the head portion, an extension on the head portion at that end thereof remote from the connecting portion, and a vent-opening-forming prong struck out of the material of said extension.

11. A piercing tool for forming dispensing and air vent openings in a can top, comprising a flat body portion, a flat head portion lying in a plane parallel to and below the plane of the body portion, a connecting portion joining the head and body portions and extending in a plane oblique to the first-named planes, a dispensing-opening-forming prong and a can-bead-engaging prong struck out of the material of the head portion, an extension on the head portion at that end thereof remote from the connecting portion, and a vent-opening-forming prong struck out of the material of said extension, said connecting portion plane being related at a 45° angle to the plane of each of the head and body portions.

12. A piercing tool for forming dispensing and air vent openings in a can top, comprising a flat body portion, a flat head portion lying in a plane parallel to and below the plane of the body portion, a connecting portion joining the head and body portions and extending in a plane oblique to the first-named planes, a dispensing-opening-forming prong and a can-bead-engaging prong struck out of the material of the head portion, an extension on the head portion at that end thereof remote from the connecting portion, and a vent-opening-forming prong struck out of the material of said extension, said connecting portion plane being related at a 45° angle to the plane of each of the head and body portions, said tool further including a head end lever adapted to receive the thumb of a hand grasping the body portion, said head end lever being formed upon the extension and

lying in a plane at an obtuse angle to the plane of the head portion.

13. A piercing tool for forming dispensing and air vent openings in a can top, comprising a flat body portion, a flat head portion lying in a plane parallel to and below the plane of the body portion, a connecting portion joining the head and body portions and extending in a plane oblique to the first-named planes, a dispensing-opening-forming prong and a can-bead-engaging prong struck out of the material of the head portion, an extension on the head portion at that end thereof remote from the connecting portion, and a vent-opening-forming prong struck out of the material of said extension, the vent-opening-forming prong being formed at its base end with a substantially semicircular portion and at its tip end with a straight portion into which the semicircular portion merges.

14. A piercing tool for forming dispensing and air vent

openings in a can top, comprising a flat body portion, a flat head portion lying in a plane parallel to and below the plane of the body portion, a connecting portion joining the head and body portions and extending in a plane oblique to the first-named planes, a dispensing-opening-forming prong and a can-bead-engaging prong struck out of the material of the head portion, an extension on the head portion at that end thereof remote from the connecting portion, and a vent-opening-forming prong struck out of the material of said extension, said connecting portion plane being related at a 45° angle to the plane of each of the head and body portions, said tool further including a head end lever adapted to receive the thumb of a hand grasping the body portion, said head end lever being formed upon the extension and lying in a plane at an obtuse angle to the plane of the head portion, the vent-opening-forming prong being extended at an obtuse angle to the plane of the head portion and at an acute angle to the plane of the head end lever, said vent-opening-forming prong being disposed in a plane at an acute angle to the plane of the dispensing-opening-forming prong.

15. A piercing tool for forming dispensing and air vent openings in a can top, comprising a flat body portion, a flat head portion lying in a plane parallel to and below the plane of the body portion, a connecting portion join-

ing the head and body portions and extending in a plane oblique to the first-named planes, a dispensing-opening-forming prong and a can-bead-engaging prong struck out of the material of the head portion, an extension on the head portion at that end thereof remote from the connecting portion, and a vent-opening-forming prong struck out of the material of said extension, the vent-opening-forming prong being formed at its base end with a substantially semicircular portion and at its tip end with a straight portion into which the semicircular portion merges.

16. A piercing tool for forming dispensing and air vent openings in a can top, comprising a flat body portion, a flat head portion lying in a plane parallel to and below the plane of the body portion, a connecting portion joining the head and body portions and extending in a plane oblique to the first-named planes, a dispensing-opening-forming prong and a can-bead-engaging prong struck out of the material of the head portion, an extension on the head portion at that end thereof remote from the connecting portion, and a vent-opening-forming prong struck out of the material of said extension, the vent-opening-forming prong being formed at its base end with a substantially semicircular portion and at its tip end with a straight portion into which the semicircular portion merges, the general plane of the vent-opening-forming prong being acutely related to the head portion and to the dispensing-opening-forming prong respectively.

17. A piercing tool for forming dispensing and air vent openings in a can top, comprising a flat body portion, a flat head portion lying in a plane parallel to and below the plane of the body portion, a connecting portion joining the head and body portions and extending in a plane oblique to the first-named planes, a dispensing-opening-forming prong and a can-bead-engaging prong struck out of the material of the head portion, an extension on the head portion at that end thereof remote from the connecting portion, and a vent-opening-forming prong struck out of the material of said extension, said tool further including a head end lever of flat formation lying in a plane offset upwardly from and parallel to the plane of the head portion, and a connecting part inclined relative to the planes of the head portion and head end lever and integrally joining the same.
